EDOUARD DUBIED & CIE., OF COUVET, SWITZERLAND.

RACKING DEVICE FOR FLAT-BED KNITTING-MACHINES.

943,921.

Specification of Letters Patent. Patented Dec. 21, 1909.

Application filed November 3, 1908. Serial No. 461,354.

To all whom it may concern:

Be it known that we, EDOUARD DUBIED, a citizen of the Republic of Switzerland, residing at Couvet, in the Canton of Neuchâtel, Republic of Switzerland, (whose post-office address is Couvet,) and BRUNO POPP, a citizen of the Republic of Switzerland, residing at Couvet, in the Canton of Neuchâtel, Republic of Switzerland, (whose post-office address is Couvet,) have invented certain new and useful Improvements in Racking Devices for Flat-Bed Knitting Machines; and we do hereby declare the following to be a full, clear, and exact description of the invention, such as will enable others skilled in the art to which it appertains to make and use the same, reference being had to the accompanying drawings, and to characters of reference marked thereon, which form a part of this specification.

In racking appliance for flat knitting machines wherein a stepped shogging cam is employed for adjusting the needle bed, provision has not heretofore been made to limit the turning of the stepped shogging cam when racking the needle bed, it happened therefore, when working the stepped shogging cam rapidly, that the revolution of the stepped shogging cam was either not sufficient or too extensive, consequently a subsequent adjustment to obtain accuracy was still necessary.

The object of the present invention is to obtain an exact adjustment of the needle bed by a single movement of the stepped shogging cam. This is accomplished by an arrangement of ratchets and pawls, operated in the manner hereinafter described, by which the stepped shogging cam cannot turn more than one step, whether the appliance be driven by hand or by treadle.

In the accompanying drawings are given examples of the manner in which our invention is carried out.

Figure 1 illustrates the central position of the needle beds. Fig. 2 shows the relative positions of the needle beds when one of the needle beds has been moved three needles to the right, and Fig. 3 shows the relative positions of the needle beds when one of the needle beds has been moved three needles to the left. Fig. 4 is a front view partly in section, Fig. 5 an end view and Fig. 6 a plan illustrating part of a knitting machine embodying our improvements. Fig. 7 is a

developed view of the stepped shogging cam. Fig. 8 is a section on the line A—B in Fig. 4 and showing the switch lever thrown back, and Fig. 9 a section on the line C—D in Fig. 4, also with the switch lever thrown back. Fig. 10 is a view similar to Fig. 8, but with the switch lever thrown forward while Fig. 11 is a view similar to Fig. 9 but with the switch lever thrown forward. Fig. 12 is a side view of the machine showing the means for operating the same by a treadle, and Fig. 13 is a plan view.

The front needle bed 1 carries a projection 2 furnished with two guiding bolts 3 and 4 between which a stepped shogging cam 5 engages. This scale is rotatably mounted on an axle 6 and between a washer 7 and the machine frame 8. The depths of the steps of the stepped shogging cam correspond to the divisions of the needle bed. The axle 6 is screwed into the machine frame 8. The stepped shogging cam 5 carries loosely on its axle tree 9 a switch lever 10, furnished with an outer pawl 13 mounted on a pivot 11, and with an inner pawl 14 mounted on a pivot 12. These pawls are kept on their pivots by washers 15 and 16 and screws 17 and 18. The pawl 13 engages with a ratchet 21 and the pawl 14 with a ratchet 22, the teeth of these ratchets being inclined in opposite directions; springs 19 and 20 maintain the pawls in engagement with their respective ratchets. The ratchets are rigidly connected to the stepped shogging cam 5 and are arranged on both sides of the lever 10.

The lever 10 carries two piston chambers 23, 24, furnished with pistons 25, 26, which latter are pressed outwardly by springs 27 and 28. Each piston is provided with two fixed nuts 29 and 30 which form a stop for limiting the innermost position.

Upon the outer square extremity 31 of the axle is attached, by means of a washer and a screw 34 and prevented from turning, a plate 33 formed with an abutment 32 against which the pistons 25 and 26 rest when the lever 10 is in its mid-position (Fig. 5). The plate 33 carries two pins 35, 36, one of which lies in the path of the pawl 13 and the other in the path of the pawl 14; the latter pawl being provided with a nose 37 to insure of it engaging with the pin 36. Connected to the scale 5 is a notched seg-

ment 38 into the notches of which a pawl 39 engages; a spring 40 holding the pawl 39 in engagement with its segment and thereby retaining the scale 5 in the position to which it has been brought by the lever 10. The pawl 39 is pivotally mounted upon the machine frame 8 by a screw 41.

The certain racking of the front needle bed over one or more needles takes place in 10 the following manner. By throwing the lever 10 over from its mid-position (Fig. 5) to its rearward position (Figs. 8 and 9) the pawl 13 rotates the toothed segment 21 to the extent of one tooth, and at the same 15 time the stepped shogging cam 5 is turned one degree, the toothed segment 21 being fixed to the stepped shogging cam, the divisions of which correspond with the teeth of the segment 21. The effect of moving the 20 lever 10 rearwardly will be to press the piston 25 against the abutment 32 (Figs. 8 and 9) and to compress the spring 27. Consequently, upon releasing the lever 10, the 25 pressure of the spring 27 forces it back to its mid position (Fig. 5). The path of the 30 switch lever from its mid position to where the piston box 23 gets to rest on the abutment 32 is so designed that the switch lever cannot turn the stepped shogging cam 5 by 35 more than one degree or division. The effect of turning the stepped shogging cam 5 over one step is, owing to the guiding bolts 3 and 4 being fixed to the needle bed 1, to push the needle bed one needle-division to the 40 right. Each time the lever 10 is moved rearwardly the front needle bed is moved one needle to the right. In order to avoid that the pawl 14 engages with the toothed segment 22, while the switch lever returns 45 from the rearward position to the mid position, the nose 37 of the pawl 14 passes over the pin 36 and the pawl 14 is thus raised off the teeth of the toothed segment 22.

If the lever 10 be drawn forward (Fig. 45 11) from its mid position (Fig. 5) the pawl 14 engages with the tooth segment 22, moves it, together with the stepped shogging cam 5, one division forward and shifts the guiding bolts from the position A (Fig. 7) into 50 the position C, with the effect that the front needle bed 1 is moved over one needle to the left. The pawl 13, during the forward movement of the lever 10 passes over the pin 35 and is thereby raised off the teeth of the 55 segment 21, for the purpose of allowing the switch lever 10 to return freely to its mid position (Fig. 10). The switch lever 10, when being moved to the forward position, presses the piston 26 (Figs. 10, 11) against 60 the abutment 32 and compresses the spring 28. The effect of this will be that, upon releasing the racking lever 10, the pressure of the spring 28 against the abutment 32 returns the switch lever to the mid position. 65 The path of the switch lever 10 from its mid

position to where the piston box 24 comes to rest on the abutment 32 is so designed that the switch lever cannot turn the stepped shogging cam by more than one division. Each forward movement of the switch lever 70 10 racks the front needle bed over one needle to the left.

If it be desired to move the needle bed more than one needle division to the left or to the right, then the lever 10 is vibrated to 75 the one or the other side, as the case may be, as many times as the desired number of needle divisions.

Figs. 12 and 13 illustrate respectively in face view and in plan, by way of example, 80 treadle means for actuating the lever 10. 43 and 44 are two pedals, one of which has its axis toward the toe and the other its axis toward the heel of the foot. Both pedals are connected to a rod 42, which engages a 85 lever 46 mounted upon a shaft 45, arranged coaxially with the lever 10. To move the needle bed in either the one direction or the other, the right or the left pedal is depressed.

According to the arrangement shown in 90 Figs. 14, 15 and 16, a single pedal 47 is pivoted at its center and is connected by a rod 42 with the lever 46 mounted on the shaft 45. By pressing down the pedal on the one or the other side of its pivot the needle bed 95 may be moved, to the right or to the left.

What we claim is:—

1. In a racking appliance for knitting machines, the combination of a needle bed 100 having two guiding bolts, a shogging cam turning between the said guiding bolts, the depths of the steps of the said shogging cam corresponding to the divisions of the needle bed, a switch lever for turning the cam by one division, means for returning said switch 105 lever automatically to its mid position when having turned the cam by one division, and pawls and ratchets for allowing said cam to move but one step at a time.

2. In a racking appliance for knitting 110 machines, the combination of a needle bed having two guiding bolts, a turning axle fixed on the frame of the machine, a shogging cam loosely mounted on the said turning axle and engaging between the two guiding bolts, the depths of the steps of the said cam corresponding to the divisions of the needle bed, a toothed segment arranged on the axis of the cam, a spring controlled pawl for securing the cam in the desired positions, and engaging with the teeth of the said segment, a switch lever for turning the cam by one division, substantially as described.

3. In a racking appliance for knitting 115 machines, the combination of a needle bed having two guiding bolts, a turning axle fixed on the frame of the machine, a shogging cam loosely mounted on the said turning axle and engaging between the two guiding bolts, the depths of the steps of the 120

125

130

said cam corresponding to the divisions of the needle bed, a toothed segment arranged on the axis of the cam, a spring controlled pawl for securing the cam in the desired 5 positions, and engaging with the teeth of the said segment, two ratchets rigidly connected to the cam, the teeth of the said ratchets being inclined in opposite directions, a switch lever also loosely mounted on the axis of the 10 cam, and two pawls pivoting on the said switch lever and serving to engage with the ratchets, substantially as described.

4. In a racking appliance for knitting machines, the combination of a needle bed having two guiding bolts, a turning axle fixed on the frame of the machine, a shogging cam loosely mounted on the said turning axle and engaging between the two guiding bolts, the depths of the steps of the said cam corresponding 15 to the divisions of the needle bed, a switch lever for turning the cam by one division, the said lever carrying two piston chambers furnished with pistons, which latter being pressed outwardly by springs, 20 and an abutment lying in the path of the said pistons and between the same, substantially as described.

5. In a racking appliance for knitting machines, the combination of a needle bed having two guiding bolts, a turning axle fixed 25

on the frame of the machine, a shogging cam loosely mounted on the said turning axle and engaging between the two guiding bolts, the depths of the steps of the said shogging cam corresponding to the divisions of the needle 30 bed, a switch lever having two pawls, two ratchets, the teeth of which being inclined in opposite directions, and means for disengaging one pawl from its ratchet while the other pawl is in engagement with its 35 ratchet when the switch lever is returned to its mid-position.

6. In a racking appliance for knitting machines, the combination of a needle bed having two guiding bolts, a shaft, a shogging 40 cam mounted on the said shaft, a lever also mounted on the shaft, a rod connecting the said lever with a single pedal, the latter pivoting at its center, an arrangement of ratchets and pawls and a switch lever for 45 turning the shogging cam by one division, substantially as described.

In testimony whereof, we have signed our names to this specification in the presence of two subscribing witnesses.
